UNITED STATES PATENT OFFICE.

JOSEPH C. ANDEREGG, OF ALGOMA, WISCONSIN.

MOP.

Application filed September 3, 1927. Serial No. 217,404.

This invention relates to mops and it is an object of the invention to provide a mop of this kind constructed in a manner permitting it to be employed for all around use.

5 It is also an object of the invention to provide a mop of this kind wherein the head constitutes a wire disposed in irregular path and which is provided at its central portion with means whereby it may be effectively engaged with an operating handle.

10 The invention consists in the details of construction and in the combination and arrangement of the several parts of my improved mop whereby certain important advantages are attained and the device rendered simpler, less expensive and otherwise more convenient and advantageous for use, as will be hereinafter more fully set forth.

15 The novel features of my invention will hereinafter be definitely claimed.

In order that my invention may be the better understood, I will now proceed to describe the same with reference to the accompanying drawing, wherein:

20 Figure 1 is a view in top plan of a mop constructed in accordance with an embodiment of my invention, the swathe being diagrammatically indicated by broken lines;

25 Figure 2 is a view in side elevation of the structure as illustrated in Figure 1, the swathe being omitted;

30 Figure 3 is a fragmentary detailed sectional view taken substantially on the line 3—3 of Figure 2.

35 As herein disclosed, my improved mop comprises a head H formed of a single strand of wire of requisite gauge and possessing a certain degree of inherent resiliency. The central portion of this strand is bent to provide two elongated straight arms 1 slightly diverging from the outer connected end portions 2 forming a substantially V-shaped tang, the ends of the sides being formed to provide the shoulders 3. 40 These arms 1 constitute means whereby the head H may be effectively connected with the operating member M.

45 The operating member M at one end portion is provided with a recess 4 in which is adapted to be received the arms 1, said end portion of the handle member having disposed thereover a metallic cap 5 provided with the slot 6 registering with the recess 4. As the arms 1 are forced within the recess 4 they will move inwardly one toward the other until the shoulders 3 enter the recess

4, whereupon the arms 1 will automatically separate causing the shoulders 3 to engage inwardly of the applied cap 5 at the ends of the slot 6 therein.

50 Extending in opposite directions from the outer ends of the arms 1 are the substantially duplicate arms 7 each disposed in an irregular or zigzag path with the various portions of the arm coplanar. By this formation of the arms 7 a relatively broad head is provided and which is preferably disposed on an angle of approximately 45° with respect to the arms 1. Each of these arms 7 is adapted to be threaded through a 55 sheathing or casing 8 for a mop swathe 9 resulting in an effective mop structure for all around use. It is to be noted that the outer end portion of each of the arms 7 constitutes substantially an open loop, thus assuring the maintenance of the swathe in applied position.

55 From the foregoing description it is thought to be obvious that a mop constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A mop comprising a single length of wire formed intermediate its ends to provide a substantially V-shaped tang, portions of the wire extending to form an arm from each side of said V-shaped tang and each terminating in a return bend forming an open loop, said arms and looped portions being designed to receive a mop swathe, and a handle having a slot in one end designed to receive said tang.

2. A mop comprising a single length of wire formed intermediate its ends to provide a substantially V-shaped tang, portions of the wire extending to form an arm from each side of said V-shaped tang and each terminating in a return bend forming an open loop, said arms and looped portions being designed to receive a mop swathe, a shoulder formed at the point of joinder be-

tween each arm and the adjacent portion of the tang, and a mop handle having means at one end for receiving said tang and for providing a wall against which said shoulders may abut upon the spreading of the arms, to prevent accidental disengagement of the tang from the handle.

3. A mop comprising a single length of wire formed intermediate its ends to provide a substantially V-shaped tang, the portions of wire extending to form an arm from each side of said V-shaped tang and

each terminating in a return bend forming an open loop, said arms and looped portions being designed to receive a mop swathe, ¹⁵ and a handle having a slot in one end designed to receive said tang, said arms and loops being arranged in the same plane, and said tang being arranged at an acute angle to said plane.

In testimony whereof I hereunto affix my signature.

JOSEPH C. ANDEREGG.
